UNITED STATES PATENT OFFICE.

AXEL ALBIN STROM, OF CICERO, ILLINOIS.

RAILWAY-SWITCH STAND.

SPECIFICATION forming part of Letters Patent No. 394,415, dated December 11, 1888.

Application filed October 7, 1885. Serial No. 179,276. (No model.)

To all whom it may concern:

Be it known that I, AXEL ALBIN STROM, of the town of Cicero, county of Cook, State of Illinois, have invented certain new and useful 5 Improvements in Railway-Switch Appliances, of which the following is a full, clear, and exact description.

The object of my invention is to provide an appliance for moving railway-switches, all 10 the parts and joints of which are fully protected from rain, snow, rust, sand, and dirt, and which offers the greatest security against injury by being tampered with by unauthorized persons; and my invention is in the 15 nature of an improvement upon that set forth in the patent to David Bowen, No. 324,526, granted August 18, 1885. In that patent the inventor describes a mode of operating the switch-rails from a vertical switch-stand, or 20 one in which the connecting-bar is moved in a straight line by a vertical revolving spindle, which consists in interposing between the vertical spindle and the connecting-bar a 25 mechanical movement in the form of a locomotive slot-link, or one in which a revolving crank engages the cross-bar of a yoke secured to the connecting-rod, whereby the revolution of the crank through the spindle moves the connecting-rod in a straight line. While the 30 construction defined in Bowen's patent is operative and the principle involved is one of great merit, I have found that the details of construction are susceptible of improvement to confer increased durability, security, and 35 consequent effectiveness to the device, and these improvements, which I will now proceed to describe, constitute my invention.

In the accompanying drawings, Figure 1 is 40 an elevation of the switch-stand with the rail-connection and the rails in section. Figs. 2 and 3 are vertical central sections of the stand, and Figs. 4, 5, and 6 are views in detail.

The switch-stand A is made of cast-iron or other suitable material and contains the entire appliance for moving the switch-rails, except an ordinary switch-lever, O O, and the connecting-rod B and tie-bar q. The top of the switch-stand A is the plate a, cast in one piece with the switch-stand A. The plate 45 a is shown in Fig. 6. It is provided with an opening which furnishes a bearing for the stem g of the crank H. The plate a is also

provided with suitable slots, b b b, to receive the arm of the lever O. The switch-stand A is hollow to allow the placing within it of the 55 stem g of the crank H. The lower portion of the switch-stand A is sufficiently large to secure a firm support and to admit of the play within it of the crank H. There is also a bearing, D, for the stem g of the crank H 60 in the lower portion of the switch-stand A. The bottom plate, E, is shown in Fig. 4. It is slightly thicker at the sides e e than elsewhere, so as to provide ways upon which slides the yoke S. The switch-stand A fits 65 over the bottom plate, E, and is provided with flanges at the bottom. The flanges have slots, through which are driven the spikes which fasten the switch-stand in its place.

G is the target upon the stem of the crank 70 H. The connecting-rod B and tie-bar q are made in one piece, as shown in Fig. 1. The tie-bar q is provided with clamps x x, which are so constructed as to clasp firmly not only the flange but also the neck of the rail, as 75 shown in Fig. 5. The bridle-bars are constructed with similar clamps.

The end of the connecting-rod B, which passes into the lower portion of the switch-stand A through an opening near the bottom 80 of the stand made for that purpose, is provided with a yoke, S, which slides upon the elevated sides e e of the bottom plate, E. A washer, W, plays in the yoke S, provided with flanges m m, which slide upon the yoke. 85 The end of the crank H fits in the center of the washer W, as shown in Figs. 2 and 3.

An ordinary switch-lever, O O, is keyed and riveted or otherwise fastened to the stem g of the crank H. The lever O O may be provided 90 with padlock and chain, as shown in the drawings. The interior sides of the bottom of the switch-stand A furnish a guide for the yoke S, so that it always moves in a straight line.

Z is a safety-block to prevent the movable 95 arm of the lever from being thrown up by accident when the switch is unlocked.

a' a' are slight protuberances upon the top of the switch-stand to prevent the lever from being moved too far.

I do not deem it necessary to fully describe the lever O O or the crank H, as they are the same as the forms now in constant use.

To adjust the appliance the connecting-rod

and tie-bar are first placed in the desired position, with the ends of the rails T T passing through the clamps $\alpha \alpha$, as shown in Fig. 1. The bottom plate, E, is then placed under the yoke S. The switch-stand A is then placed over the plate E, with the end of the crank H in the opening of the washer W. The switch-stand is then spiked in position and the appliance is ready for use. By raising the arm of the lever and moving it in the required direction the stem g of the crank H is turned, and with it the crank. The end of the crank turning moves the washer W and the yoke S. The yoke S, being a part of the connecting-rod and tie-bar and moving in a straight line, draws or pushes the latter, and with it the rails, to the desired position.

It will be seen that the strain of moving the connecting-rod, which in the former construction is exerted solely upon a single cross-bar or yoke - pin, is by my construction divided between the two, which may be made of increased size without requiring any change in the size or character of the washer 25 at the end of the crank. Moreover, the variation in the position of the yoke from a per-

fectly horizontal plane will have no noticeable effect in my construction, although it would seriously impede the operation of the one above referred to.

30

What I claim as new, and desire to secure by Letters Patent, is—

1. A railway-switch appliance comprising a connecting-bar having a transversely-slotted yoke formed on its inner end, a switch-stand, a vertical spindle terminating in its lower end in a crank inserted into the slot of the yoke, and lateral guides for the yoke, all as set forth.

35

2. A railway-switch appliance comprising a vertical stand and vertical spindle within the same terminating in its lower end in a crank, a connecting-rod terminating in its inner end in a transversely-slotted yoke, lateral guides for the yoke, and a flanged washer moving in the transverse slot of the yoke and secured to the lower end of the crank, as described.
